UNITED STATES PATENT OFFICE.

WALTER TURNBULL, OF NEW ORLEANS, LOUISIANA.

CAR-COUPING.

SPECIFICATION forming part of Letters Patent No. 313,963, dated March 17, 1885.

Application filed October 27, 1884. (No model.)

To all whom it may concern:

Be it known that I, WALTER TURNBULL, a citizen of the United States, residing in the city of New Orleans, in the parish of Orleans 5 and State of Louisiana, have invented a new and useful Car-Coupling, of which the following is a specification.

My invention relates to car-couplings which are operated automatically; and the objects of 10 my invention are, first, to provide a means by which railway-cars can be coupled together automatically without endangering the limbs and lives of railway employés, as also to expedite the operation of coupling up trains of 15 cars; second, to afford facilities by which cars will be coupled by a hook when all the cars are equipped with my coupler, also to provide a means by which my coupler will couple automatically with cars equipped with 20 the present link-and-pin coupler, so that my hook-coupling can be gradually adopted and replace the present link-and-pin couplers as they wear out; third, to provide a means by 25 which my coupler can be made to suit the fittings of any coupler which it is desired to replace. I attain these objects by the mechanism illustrated in the accompanying drawings, forming part of this specification, in which—

30 Figures 1 and 2 are respectively a side and plan view of my coupler, showing the coupling made with cars equipped with my coupler. Fig. 3 is a side view showing the coupling made with a car equipped with the present link-and-pin coupling. Fig. 4 is an end view showing arrangement for uncoupling the cars.

Similar letters refer to similar parts throughout the several views.

40 The buffer or draw-head B is provided with recesses in front end to admit of the hook-lever H and the link-lever L, and is also provided with a buffering-plate, P, to keep link from going to far into draw-head. The back 45 part of draw-head is made to conform to the fittings of any other style of draw-head which it may replace. The hook-lever H is shaped as shown in drawings, and is secured to draw-head by the pin i, the lever being slotted to 50 admit of a horizontal movement. This hook-lever H is provided with an eyebolt, e, to

which is attached a chain, c, which is secured to the sheave s on shaft r, which rod is secured to end of car to lift the hook-lever H to uncouple same, or to hoist the hook-lever up out 55 of the way, so that the link-coupling can be made as shown in Fig. 3.

The link-lever L is secured to draw-head by the pin N, and is provided with a hook h, at its outer end to engage with coupling-link K. 60 It is also provided with an eyebolt, o, to which a chain, b, is attached, which is secured to sheave s for lifting the link-lever L in position to couple with link K, as shown in Fig. 3, also for uncoupling the link. 65

The shaft r extends across the end of car, and is secured to the car by the bearings M. The ends of shaft r are bent as shown in Fig. 4, forming handles d, to which are secured counter-weights w to keep shaft r from turning over 70 when it is desired to maintain the hook-lever H in the position shown in Fig. 3. The sheave s is secured to the shaft r and receives the chains b and c. The diameter of this sheave is such that, when the position of the eyebolts e 75 and o are determined, one revolution of the sheave s will lift the hook-lever H and the link-lever L to the position shown in Fig. 3, so that a link-coupling can be made, and the hook-lever H and link-lever L are maintained 80 in this position by the bent handles d of shaft r hanging down and having the counter-weights w.

X is the body of freight-car, showing the relative position of same with the coupler. 85 D is a link-and-pin coupler.

Having thus described the construction of my coupler, the working of same is as follows, viz: When it is desired to couple cars which are equipped with my couplers, the hook-lever H lies horizontal and the link-lever L lies in recess in bottom of draw-head, as shown in Fig. 1, and as the cars come together the hook-lever H of one of the cars rides over the hook-lever of the other car and falls into position, as shown in Figs. 1 and 2, and, when it is desired to uncouple them, the sheave s is revolved by the handles d of the shaft r and lifts the hook H until the hooks are disengaged, when the car pulls out and the hook-lever H 100 falls back in position to be coupled again.

When it is desired to couple my coupler

- with cars equipped with the link-and-pin coupler, the sheave *s* on the shaft *r* is turned once around by the handles *d*, which lifts the hook-lever *H* up out of the way and brings the link-lever *L* in position to receive the coupling-link *K*, as shown in Fig. 3. When the link *K* secured in draw-head *D* strikes against the angle end of the link-lever *L*, it lifts same and rides under it and engages with the hook *h*. This coupling-link *K* is uncoupled by turning the sheave *s* until the hook *h* of link-lever *L* disengages with coupling-link *K*, when the car pulls out and the link-lever *L* falls back in position to be coupled again.
- Having thus described the construction and operation of my coupler, I claim as new and desire to secure by Letters Patent—
1. The combination, in an automatic car-

coupler, of the buffer or draw-head *B*, provided with the recesses in forward end for the hook-lever *H* and link-lever *L*, and the buffering-plate *P* with the hook-lever *H*, provided with pin *i* and eyebolt *e*, and the link-lever *L*, provided with the hook *h*, pin *N*, and eyebolt *o*, all substantially as set forth, and for the purpose specified.

2. In an automatic car-coupling, the combination of the buffer *B*, hook-lever *H*, and link-lever *L*, with the chains *b* and *c*, sheave *s*, shaft *r*, handles *d*, bearings *m*, and counter-weights *w*, all substantially as described, and for the purpose specified.

WALTER TURNBULL.
